INTERNAL SHOE DRUM BRAKE

Leslie Cyril Chouings, Leamington Spa, England,
assignor to Automotive Products Company
Limited, Leamington Spa, England

Application October 18, 1943, Serial No. 506,735
In Great Britain October 9, 1942

5 Claims. (Cl. 188—78)

This invention relates to internal shoe drum brakes of the kind comprising two arcuate shoes each having an anchorage abutment at one end, both shoes extending from their abutments in the same circumferential sense and the shoes being operated by a single spreading means acting directly on to the free end of one shoe, and through a linkage on to the free end of the second shoe.

It is the object of the invention to provide a simple and efficient brake of this kind.

In a brake which is of the kind referred to and in which the linkage comprises two interconnected bell-crank levers, the first of which levers is acted upon by the spreading means, while the second is pivoted on the free end of the second shoe and engages a fixed abutment with one of its arms, the present invention is characterised by the fact that the first bell-crank lever is pivotally mounted on the fixed support of the brake, and, through its interconnection with the other bell-crank lever, limits the inward movement of the second shoe when the brake is released.

Preferably the fixed abutment comprises an adjustable stop serving to adjust the drum clearance of the second shoe, said adjustable stop conveniently comprising a strut of variable length operatively connected between the second bell-crank lever and the anchorage abutment of the first shoe. The spreading means may act as an anchorage for the first bell-crank lever when the brake is released. Moreover at least one arm of each bell-crank lever is preferably double so as to extend on both sides of a radial web forming part of the second shoe, said bell-crank levers conveniently being connected together by a thrust member comprising a pair of strips held in spaced parallel relationship so as to extend alongside opposite side surfaces of the shoe web. Movement of the shoe in an axial direction is preferably prevented by a spring finger, which resiliently maintains said web in contact with a shoe-locating projection carried by the fixed support of the brake, the shoe-locating projection being provided with a screw-threaded adjustment member against which the shoe web bears slidably. If desired a single adjusting means may serve to move the anchorage of the first shoe and the adjustable stop for the second bell-crank lever.

The invention is illustrated in the accompanying drawings, in which:

Figure 1 is an elevation of one construction of brake, the drum being shown in section;

Figure 2 is a fragmentary sectional plan taken on the line 2—2 of Figure 1;

Figure 3 is a fragmentary elevation of a modified adjusting device for the lower ends of the shoes; and

Figure 4 is a fragmentary sectional plan taken on the line 4—4 of Figure 3.

A drum 10 of the usual cylindrical form constitutes the rotating element of the brake, as shown in Figure 1, and is arranged to be engaged by a pair of rigid arcuate brake shoes, the first of which is indicated at 11 and the second at 12. Each shoe is of the usual T shape in cross-section comprising a web 13 and a curved flange 14, 15 to which latter the lining 15 of the brake shoe is attached. The usual fixed support of the brake, i. e. that part which does not rotate and serves as a mounting for the brake shoes, comprises a substantially tubular member 16 arranged to be secured to the axle casing or other convenient fixed part of the vehicle, said tubular member 16 being formed integrally with a depending bracket 17 and an upwardly extending bracket 18. A circumferentially grooved anchor 25 pin 19, fixedly mounted upon the bracket 17, is arranged to be engaged by a notch 20 in the end of the web 13 of the shoe 11, thereby allowing said shoe to move angularly into and out of engagement with the interior of the drum 10. A similar fixed anchor 21 is provided for engagement by the notched portion 22 of the shoe 12. Spreading means, indicated generally at 23, are secured to the bracket 18 and conveniently comprise a hydraulic cylinder 24 containing a pair 30 of pistons 25 and 26 adapted to be spread apart by admitting liquid under pressure through an inlet opening 27. The piston 25 is formed with a shoulder 28 arranged to abut against the corresponding end of the cylinder 24 so as to enable said piston to act as an anchorage; in the case of the piston 26 a knurled head 29 provides a shoulder 30 adapted to engage the end of the cylinder for a similar reason, but the head 29 is in addition arranged to serve as an adjustment 45 for the first shoe 11. Thus a stem member 31, screw-threaded into the piston 26, is slotted diametrically at 32 to embrace the end of the web 13 of the shoe 11, so that by rotating the head 29 the stem member 31 can be forced outwards 50 to the desired extent in order to adjust the clearance between the lining 15 and the drum 10. A spring finger 33 preserves the adjustment of the head 29 in the usual manner.

The means used for applying the second shoe 12 comprise a first bell-crank lever 34 mounted

for angular movement upon a fulcrum pin 35 which is securely attached to the bracket 18 of the fixed support. The bell-crank lever 34 comprises an upwardly directed arm 36 engaging with the piston 25, and also a substantially horizontal arm 37 which is double or bifurcated so as to extend on both sides of the web of the shoe 12, said arm 37 being formed at its outer end with a notch 38 adapted to engage pivotally with the narrow but rounded upper end of a thrust member 39. This is also of double construction so as to engage with both parts of the arm 37, and comprises a pair of strips 40 held in parallel relationship by spacing members 41. The lower end of the thrust member 39 engages with a second bell-crank lever 42. The second bell-crank lever 42 comprises a pair of identical substantially triangular plates 43 disposed one on each side of the web 13 of the shoe 12 and pivoted to the latter by means of a fulcrum pin 44. The lower end of the thrust member 39 pivotally engages with notches 45 in what constitutes the substantially horizontal arm 46 of the bell-crank lever, while a substantially vertical arm, indicated at 47, is formed with a notch 48 which engages pivotally with the end of the bifurcated portion 49 of a fixed abutment device indicated generally at 50.

The fixed abutment device 50, which operates in conjunction with the anchorage 19, is arranged to be adjustable and comprises a non-rotatable bearer member 51 having an arcuate head portion 52 arranged to engage the groove in the anchor pin 19 and a cylindrical spigot 53; mounted rotatably upon the spigot 53 so as to bear against a shoulder 54 is an adjusting sleeve 55 having a knurled head portion 56 engaged by a retaining spring finger 57. The adjusting sleeve 55 is internally screw-threaded for engagement with a corresponding thread upon the outside of a stem 58, which latter extends through a slotted retaining lug 59 and is formed with the bifurcated portion 49 to embrace the end of the web of the shoe 12. Thus the bifurcated portion 49 serves as a fixed but adjustable anchorage for the arm 47 of the bell-crank lever 42, and, owing to the provision of the slotted lug 59, it also acts to prevent lateral displacement of the lower end of the shoe 12 in a direction parallel with the drum axis.

Lateral displacement of each of the shoes 11 and 12 is also prevented by a shoe-locating projection 60 secured to the fixed support 16 by screws 61. The extremity of the projection 60 is threaded to receive a grub screw 62, against the inner end 63 of which the web 13 of the brake shoe is adapted to bear, as will be seen more clearly in Figure 2. The shoe is held resiliently in this position by a spring finger 64 having a reinforced end portion 65, said finger being secured to the projection 60 by a pair of screws, one of which is indicated at 66. A lock nut 67 preserves the adjustment of the grub screw 62.

The usual two pull-off springs which draw the shoes together for releasing the brake are indicated at 68 and 69. Each is anchored at one end to a pin 70 projecting from the web of the shoe 12, and at its other end said spring engages with a dead-centre link in the form of a substantially triangular plate 71. This plate is pivoted at 72 to the web 13 of the shoe 11. The turned-over end of the spring engages with a notch 73 in the plate, so that by rotating said plate the axis of the spring can be caused to

pass the axis of the pin 72. The spring naturally tends to move the plate 71 in either direction away from this dead-centre position, but such movement in one direction is prevented by the engagement of the corner portion 74 of the plate with the inside of the flange 14, thus retaining the spring in its operative stretched condition. To release the tension in the spring the corner portion 74 is moved away from the flange 14, and after the dead-centre position has been passed the tension in the spring can be completely released before the spring is disconnected.

The normal forward direction of drum rotation of the brake shown in Figure 1 is clockwise, and when the spreading means 23 are operated with the drum rotating in this direction the first shoe 11 acts as a simple leading shoe taking its abutment upon the anchor pin 19. At the same time outward movement of the piston 25 causes the first bell-crank lever 34 to be moved in an anti-clockwise direction, thus moving the thrust member 39 in a downward direction. The bifurcated portion 49 of the fixed abutment device 50 then acts as an anchorage, so that the second bell-crank lever 42 is caused to move in an anti-clockwise direction about said bifurcated portion, thus forcing the pin 44 towards the left and applying the second shoe 12 to the drum 10; during this action the upper end of the shoe 12 engages the anchor pin 21, so that this shoe also acts in a leading sense for forward rotation of the drum. With the drum 10 rotating in an anti-clockwise direction both shoes 11 and 12 operate as trailing shoes, the shoe 12 being moved outwards into engagement with the drum 10 by the action of the bell-crank levers 34 and 42.

As mentioned above, the first shoe 11 is adjusted by means of the head 29, and it will now be appreciated that the clearance of the shoe 12 is regulated by turning the head 56 so as to vary the operative length of the fixed abutment device 50, the bell-crank lever 34 taking its abutment upon the cylinder 24 through the medium of the external part of the hydraulic piston 25.

If desired the fixed abutment device 50 may be arranged to effect simultaneously the adjustment of both shoes 11 and 12, and a modified form of shoe anchorage embodying this feature is shown in Figures 3 and 4. A somewhat V-shaped housing 75 is secured to the bracket 17 by a pair of studs and nuts 76, and is formed with a pair of mutually inclined bores 77 and 78 each containing a corresponding freely slidable plunger member 79 or 80. The plunger member 79 has a head 81, which is slotted at 82 to embrace the web of the first shoe 11, the base of the slot being convex to engage pivotally with a semi-circular notch 83 formed in the lower end of the shoe 11. The outer end of the plunger member 80 is slotted diametrically, as indicated at 84, so as to receive the web at the lower end of the second shoe 12, the pair of end surfaces 85 being arranged to bear each against a convex surface 86 at the lower part of the corresponding plate 43 constituting the bell-crank lever 42. The adjacent end part of the housing 75 is also slotted at diametrically opposite positions to accommodate the web of the shoe 12, thus locating said shoe against axial displacement. The inner ends of the plungers 79 and 80 are sloped, as indicated at 87, for engagement with a cam member 88 having a pair of ears 89 and 90, these being of triangular shape and being arranged 75 to slide within corresponding grooves 91 and 92

formed in the housing 75. The cam member 88 is screw-threaded at its central part and constitutes a nut mounted upon a screw-threaded stem 93 having a head 94 adapted to bear against an annular surface 95 of the housing 75; axial displacement of the stem 93 in an outward direction is prevented by a plate 96. When the brake is in operation the plunger member 79 constitutes the anchorage abutment for the shoe 11, while the plunger member 80 forms a corresponding anchorage for the bell-crank lever 42.

When it is desired to readjust the shoes in order to take up wear of the linings the stem 93 is rotated by means of a suitable key applied to its squared end portion 97, the direction of rotation being such that the ears 89 and 90 of the cam member 88 force apart the plunger members 79 and 80 to the requisite amount.

It will be understood that the arrangements which have been described are given merely by way of example and that the construction may be modified to suit requirements. For instance, various forms of spreading means may be employed, such, for example, as the mechanical expander device described in United States of America patent specification No. 2,238,361, dated April 15, 1941.

The improved brake is more particularly applicable to the steering mechanism of endless track vehicles, in which brakes are used to retard the movement of the track on one or other side of the vehicle for steering purposes. Its use is not, of course, limited to this particular application.

What I claim is:

1. In a brake including a support, a shoe mounted on the support, an actuator, and a fixed abutment device on the support at the opposite end of the shoe from the actuator, means for exerting force against the end of the shoe remote from the actuator comprising two interconnected bell-crank levers, the first of which is acted upon by the actuator and is pivotally mounted on the support, the second of which is pivoted on the remote end of the shoe and engages the fixed abutment device with one of its arms, the first bell-crank lever being adapted through its interconnection with the other bell-crank lever to limit the inward movement of the shoe when the brake is released, said abutment device including an adjustable stop engaging the second bell-crank lever and which serves to adjust the clearance of the shoe.

2. A brake as claimed in claim 1, wherein the actuator acts as an anchorage for the first bell-crank lever when the brake is released.

3. In a brake including a support, two shoes

mounted on the support, an actuator, and an anchor on the support opposite the actuator, in combination, means for exerting force against the end of one shoe near the anchor comprising two interconnected bell-crank levers, the first of which is acted upon by the actuator and is pivotally mounted on the support, and the second of which is pivoted on the remote end of the shoe and engages the anchor with one of its arms, the first bell-crank lever being adapted through its interconnection with the second bell-crank lever to limit the movement of the shoe when the brake is released, and a single adjusting means serving to move the anchorage of the second bell-crank lever and also of the other shoe.

4. In a brake including a support, a shoe mounted on the support, an actuator, and a fixed abutment on the support at the opposite end of the shoe from the actuator, means for exerting force against the end of the shoe remote from the actuator comprising two interconnected bell-crank levers, the first of which is acted upon by the actuator and is pivotally mounted on the support, the second of which is pivoted on the remote end of the shoe and engages the fixed abutment with one of its arms, the first bell-crank lever being adapted through its interconnection with the other bell-crank lever to limit the inward movement of the shoe when the brake is released, and means for preventing movement of the shoe in an axial direction comprising a spring finger which resiliently maintains the shoe web in contact with the support.

5. In a brake including a support, a shoe mounted on the support, an actuator, and a fixed abutment on the support at the opposite end of the shoe from the actuator, means for exerting force against the end of the shoe remote from the actuator comprising two interconnected bell-crank levers, the first of which is acted upon by the actuator and is pivotally mounted on the support, the second of which is pivoted on the remote end of the shoe and engages the fixed abutment with one of its arms, the first bell-crank lever being adapted through its interconnection with the other bell-crank lever to limit the inward movement of the shoe when the brake is released, and means for preventing movement of the shoe in an axial direction comprising a projection on said support having thereon a screw threaded adjustment member against which the shoe web bears slidably, and a spring finger which resiliently maintains the shoe web in contact with said adjustment member.

LESLIE CYRIL CHOUINGS.
